By C. P. Goepel, attorney.

UNITED STATES PATENT OFFICE.

KAREN MARIE HANSEN, OF SILKEBORG, DENMARK.

DOLL.

1,407,270.

Specification of Letters Patent. Patented Feb. 21, 1922.

Application filed March 6, 1919. Serial No. 280,887.

To all whom it may concern:

Be it known that I, KAREN MARIE HANSEN, a subject of the King of Denmark, and resident of Silkeborg, in the State of Denmark, have invented certain new and useful Improvements in Dolls, of which the following is a specification.

The dolls, which children are given to play with, are generally so constructed, that it is not possible—or at least only with great difficulty—to make them stand upright on their legs. On account of this deficiency the doll will be a less amusing and serviceable toy, especially for smaller children, and entails further the drawback that the doll is easier broken by falling over, when attempts to make it stand are made, or when it is brought into an uncertain position.

This invention relates to a doll, in which the described deficiencies are sought to be relieved. It consists mainly of the doll arranged upon a foot piece, the bottom of which is slightly convexed, and the top side provided with a cylindrical part to which the lower edge of the doll's body is attached in an easy and convenient manner.

When such a doll is set into rotation by the hand, it will continue to rotate for a longer or shorter time. If the doll, when being set into rotation, is simultaneously brought out of its perpendicular position, it will perform circular movements over the foot piece besides rotating. The doll stands firmly and will not upset if subjected to softer blows or pushes.

The accompanying drawings illustrate one construction of the device, which is characteristic for the present invention.

Fig. 1 is a front view of the doll, and Fig. 2 is the same view partly in section. The doll is mounted upon a foot piece 1, convex at its under side, the plane top side of which forms the greatest diameter of the doll. In the middle of this side a vertical

rod or bar 2 is attached, running up through the body of the doll into the head 3. The top end of this bar 2 is moulded in the head by means of plaster of paris or any other similar material or attached hereto in any other manner. The center of curvature of 50 the convex under surface is preferably substantially at the upper end of the rod 2 so that while the convexity is not great, and is inconspicuous, the structure will not be top-heavy.

The body of the doll consists of a case 4 mounted around the rod 2 and filled with a suitable material as e. g. wood flock, tow or suchlike.

The lower edge 5 of the case 4 is attached 60 to the foot piece, which to this end is supplied with a cylindrical part that fits into the edge 5 of the case 4.

Finally the head of the doll is either sewn or glued to the case 4 in known manner.

The shape and the fitting up of the doll as well as the stuff of which it is made can naturally be varied in many ways without in any manner whatever affecting the principle of this invention.

I have shown an embodiment of my invention, but it is clear that changes may be made therein without departing from the spirit thereof as defined in the appended claim.

What I claim is:

An improved doll comprising a base shaped as a section of a ball, the lower side of said base being only slightly curved, the top side of said base being plane and cylindrical 80 along its edge, and a doll body resting upon the plane top side of the base and having its lower edge extending about the cylindrical portion of the base.

In testimony whereof I affix my signature 85 in presence of two witnesses.

KAREN MARIE HANSEN.

Witnesses:
